CLAIM

The ornamental design for a juicer funnel as shown and described.

DESCRIPTION

FIG. 1 is an exploded front view of a juicer funnel showing my new design;

FIG. 2 is an exploded rear view of the juicer funnel;

FIG. 3 is an exploded right side view of the juicer funnel;

FIG. 4 is an exploded left side view of the juicer funnel;

FIG. 5 is an exploded top view of the juicer funnel;

FIG. 6 is an exploded bottom view of the juicer funnel;

FIG. 7 is an exploded top front side perspective view of the juicer funnel; and,

FIG. 8 is a top front side perspective view of the juicer funnel.

The broken lines are illustrative of portions of the juicer funnel forming no part of the claimed design.

1 Claim, 7 Drawing Sheets
